Primary Examiner — Susan E Krakower*Assistant Examiner* — Jerry Shiuan-Hua Hsu(74) *Attorney, Agent, or Firm* — Patterson Thuente Pederson, P.A.(57) **CLAIM**

I claim the ornamental design for a door panel for vehicle, as shown and described.

DESCRIPTION

FIG. 1 is a front left perspective view of a door panel for vehicle, showing my new design.

FIG. 2 is a front right perspective view thereof; and,

FIG. 3 is a front view thereof.

The broken lines in the drawings illustrate portions of the door panel for vehicle that form no part of the claimed design.
